BREAST PUMP

Filed Aug. 29, 1925

INVENTOR:
ROY KEITH
BY Harry a. Beimer
ATTORNEY.

UNITED STATES PATENT OFFICE.

ROY KEITH, OF ST. LOUIS, MISSOURI, ASSIGNOR TO CHARLES P. BOBE AND HAZEL V. KEITH, BOTH OF ST. LOUIS, MISSOURI.

BREAST PUMP.

Application filed August 29, 1925. Serial No. 53,343.

My invention has relation to improvements in breast pumps and consists of the novel features of construction more fully set forth in the specification and pointed out in the claim.

5 Briefly the invention consists in a receptacle to which is connected a funnel and a continuously operating pump or injector. The funnel and pump are in air-tight connection with the receptacle except for the vent by 10 which the suction created by the pump may be periodically interrupted.

The object of the invention is to provide a breast pump that is simple to operate and one that has a funnel in which there is a bulbous 15 enlargement for the nipple so that in the operation of the pump the patient will suffer no discomfort. Further and other advantages will be better apparent from a detailed description of the invention in connection with 20 the accompanying drawings in which—

Figure 1 is a side elevation of my improved breast pump shown assembled for operation; and Figure 2 is a middle longitudinal section through my improved funnel.

25 Referring to the drawings, 1 represents a suitable open mouthed receptacle provided with a cork or stopper 2 in which there are two spaced openings 3 and 4. Into the opening 3 is inserted the stem 5 of a funnel 6, said funnel, it will be observed, having a bulbous 30 enlargement 7 at the juncture of the stem with the bell or funnel proper, the purpose of which enlargement will appear hereinafter.

A T-shaped tube 8 is adapted to have one 35 of its branches 9 inserted into the opening 4 in the stopper 2, while its branches 10 and 11 have applied to them a flexible vent tube 12 and hose 13 respectively. The end of the 40 hose 13 opposite to that passed over the tube 11 is connected to a hollow stem 14 projecting from the pump or injector 15, the latter being of any suitable type obtainable in the open market.

The pump 15 in the present instance is 45 adapted to being applied to a water cock or

faucet 16 and operates on the principle of the injector in that the water from the faucet discharges through the pump and causes a current of air to be induced through the stem 14 thereof. The operation of my improved 50 pump is then as follows:

Having connected the pump 15 to a faucet and turned the latter on, a current of air is induced through the hose 13 and into the pump. If the operator now presses the tube 55 12 shut with the fingers (as shown dotted on Fig. 1) a current of air will be induced into the funnel 6 so that if this funnel is disposed over the breast, a suction will be created 60 thereon, drawing the milk from the nipple 65 thereof. It is important that in this operation that the nipple be free from pressure in order to prevent constricting of the ducts therein for which purpose I have formed the bulbous enlargement 7 at the point in the funnel where the nipple will be located. In order to successfully draw the milk from the breast, the operator will now intermittently open and close the tube 12, thus alternately 70 creating suction and releasing it, thus simulating the operations of nature. The milk drawn from the breast at each moment that the tube 12 is closed, will discharge into the receptacle 1 at the succeeding moment when said tube is opened. The operation as 75 described is continued until the proper amount of fluid has been obtained to satisfy the purpose of the operation.

Having described my invention, I claim:

A funnel for breast pump receptacles, said 80 funnel comprising a bell-shaped portion for receiving the breast, a stem integrally formed with said bell-shaped portion, and a globular, bulbous, enlargement between the bell-shaped portion and the stem for receiving the nipple 85 and preventing constriction thereof.

In testimony whereof I hereunto affix my signature.

ROY KEITH.
